MULTICOLOR PRINTING PRESS

Henry A. Wise Wood, New York, N. Y., assignor
to Wood Newspaper Machinery Corporation,
New York, N. Y., a corporation of Virginia

Application March 5, 1931, Serial No. 520,293
Renewed January 30, 1934

5 Claims. (CL. 270—5)

The present invention relates to improvements in multi-color printing presses.

An object of the invention is to provide a novel arrangement of single impression and multiple 5 impression printing units, whereby a publication such, for instance, as a newspaper may be printed partly in single color and partly in multiple colors.

In a copending application, Serial No. 512,029, filed January 29, 1931, I describe an arrangement 10 of single impression and multiple impression units whereby a web may be printed in one color on one face and in a plurality of colors on the other.

An object of the present invention is to provide an arrangement whereby a web may be printed in 15 multiple colors on both faces thereof.

Another object of the invention is to provide means for printing a web in multiple colors on both faces thereof and in one color, say black, on one of said faces.

20 Another object of the invention is to provide a pair of multi-color units through which a web may be passed in succession, one unit being reversed with respect to the other, so as to perfect the web in color and also to provide means between the 25 units for slitting the web so that a portion thereof may pass by the second unit without being impressed thereby.

A further object of the invention is to provide a single impression perfecting unit and a multiple 30 impression unit with slitting means between the units whereby a part-width strip of the web may be passed through the multiple impression unit to receive a plurality of color impressions thereon, while another strip of the web avoids the multiple 35 color unit and receives impressions from the single impression unit only.

Other objects and advantages of the invention will appear in the following description of two 40 embodiments thereof and thereafter the novelty and scope of the invention will be pointed out in the claims.

In the accompanying drawings:

Figure 1 is a diagrammatic side elevation of an 45 arrangement of single-color and multi-color printing units embodying my invention; and

Fig. 2 is a similar view of a modified form of my invention.

Referring to the arrangement shown in Fig. 1, my improved printing press comprises a base 10 50 on which are mounted two perfecting units A and B. These units are alike and the description of one will suffice for the other.

The unit A comprises two printing couples, one 55 consisting of an impression cylinder 12 and plate cylinder 13 and the other of an impression cyl-

inder 14 and plate cylinder 15. Each of the plate cylinders is provided with its own inking system 16. The web a is led successively through the two couples and thence is guided to a multi-color unit C mounted above the unit A.

The multi-color unit C comprises an impression cylinder 17 against which bear four plate cylinders 18, 19, 20 and 21 respectively. Each of these plate cylinders has its own inking system 22. Over the unit B is another multiple impression 65 unit D which is similar to the unit C.

The web a passes around the impression cylinder 17 in clockwise direction, as indicated by the arrow, so as to receive impressions from the plate cylinders 18, 19, 20 and 21 in the order named. 70 Thence the web is guided over suitable rolls to the top of the unit D where it is passed in counter-clockwise direction about the impression cylinder 17 of the unit D. The web then receives impressions from the plate cylinders of the unit D 75 in the order 19, 18, 21 and 20. Thus, it will be observed that the web is printed on opposite faces thereof by the two couples of unit A and then is printed on one face by the unit C and on the other by the unit D.

Ordinarily, the color of the impressions made by the unit A will be black; although, obviously, any other color can be used and the color impressed by the plate cylinder 13 may differ from that of the plate cylinder 15 because each plate 85 cylinder has its own inking system. The four colors applied to the plate cylinders of unit C may also be different from the four colors provided by the plate cylinders of the unit D.

The units A and C are driven by a common 90 motor 23 mounted therebetween. The drive of unit A is effected by a chain belt 24 which runs from the motor to a sprocket wheel 25 fixed to the cylinder 12. Another chain belt 26 drives the impression cylinder 17, but, since the impression cylinder 17 turns in the opposite direction to the rotation of the impression cylinder 12, a reversing gear is provided between the belt 26 and the cylinder 17. This reversing gear which is not shown in the drawings, may be of any suitable type 100 such, for instance, as that shown in my copending application. Since the impression cylinder 17 is reversible the inking system 22 of each plate cylinder must also be reversible and consequently change rolls 27 are provided in each inking system, which may be adjusted like the change gears of a lathe to provide for a change in relative rotation of the fountain roll of the system with respect to the inking rolls.

The units B and D are similarly driven by a 110

common motor, but since the direction of rotation of the impression cylinder 17 in unit D is the same as that of impression cylinder 12 in unit B, it is not necessary to provide a reversing gear in the 6 drive of the unit D. However, in order to make the units all interchangeable, a reversing gear is preferably provided for the unit D as well, and the inking systems of the unit D are also provided with change rolls 27.

10 The web *a* after passing through the units A, C and D in succession, is led to a drag roll 30 of the assembling mechanism E, where it is slit by a slitter roll 31 into strips *a*¹ and *a*². A second web *b* is passed through the unit B and then 15 instead of continuing through the unit D is led to a drag roll 36 where it is slit by a slitter roll 37 into a pair of strips *b*¹ and *b*². The strip *a*² is passed about a pair of angled turning bars 32 which carry it under and into alignment with the strip *a*¹, and, similarly, the strip *b*² is passed about turning bars 38 which turn it under the strip *b*¹. All of the strips *a*¹, *a*², *b*¹ and *b*² then pass as a 20 unit to the drag roll 39 of a folder F.

In the drawings, the web *b* is shown in full 25 lines as passing only through the first printing couple 12—13 of the unit B and avoiding the printing couple 14—15. This arrangement, of course, is optional and the web may be carried also through the second couple, as indicated by 30 broken lines, so that both faces of the web will be printed.

The arrangement of units in Fig. 2 is similar to that in Fig. 1, except that a drag roll 40 and a slitter roll 41 are provided between the units C and D and a drag roll 42 and a slitter roll 43 are provided between the units B and D.

As shown in Fig. 2, a web *W* is led first through the unit A to receive single-color impressions on opposite faces thereof and then is passed through the unit C to receive multi-color impressions on one face thereof. The web is then slit by the slitter roll 41 into two strips *W*¹ and *W*². The strip *W*¹ proceeds directly to the assembly 45 mechanism E, whereas the strip *W*² is passed through the unit D in counterclockwise direction to receive multi-color impressions on the opposite faces thereof before it is led to the assembling mechanism E. It will be understood, of course, that the strip *W*² being a half width web 50 engages only one-half of the length of the cylinders in unit D.

Another web *w* is led through the unit B to receive single-color impressions on opposite faces thereof, and then is slit by the slitter roll 43 into strips *w*¹ and *w*². The strip *w*¹ is then led through the unit D side-by-side with the strip *W*², while the strip *w*² runs directly to the assembling mechanism E.

As a result of this arrangement, we find that in the assembling mechanism the strip *w*¹ is 55 printed in black on both faces (assuming that black is the color of ink employed in the units A and B) and in multiple colors on the upper face thereof; the strip *w*² is printed in black and multiple colors on both faces thereof; the strip *w*¹ is printed in black on both faces thereof and in multiple colors on the under face thereof; while the strip *w*² is printed only in black on each face thereof.

70 In the assembling mechanism E all of the strips may be brought into superposed alignment by means of turning bars 45 and the strips may be brought into mutual register by means compensating rolls 46. Thereafter the strips are all led as a unit to the drag roll 47 of the folder F.

While turning bars are provided for each strip, obviously, only the alternate strips will be turned to bring all of the strips into superposed alignment. However, any strip may be turned to one side or the other by means of the turning bars, or the strips may continue without turning to separate folding forms 48 in the folder F. It will be thus observed that by my arrangement, I provide for a wide variety of combinations of single-color and multi-color printing.

80 It will be understood that the arrangements described above are to be taken as illustrative and not limitative of my invention and that I reserve the right to make such changes in method, form, construction and arrangement of parts as 85 fall within the spirit and scope of the following claims.

I claim:

1. A web printing press comprising a single color press unit, a pair of multi-color press units, means 95 for guiding a web through the single color press unit and thence through one of the multi-color units and through the other multi-color unit in reverse direction, means for slitting the web into a plurality of strips between the two multi-color units, means for diverting one of the strips from the second multi-color unit, and means for assembling all of the strips in superposed relation.

2. A web printing press comprising a pair of multi-color press units, a single-color press unit, means for guiding a web through one multi-color unit in one direction and through the second multi-color unit in reverse direction, means for slitting the web into a pair of strips, means for diverting one of the strips from the second multi-color unit, means for guiding a second web through the single-color unit, means for slitting the second web into a pair of strips, means for guiding one of the latter strips through the second multi-color unit side-by-side with the strip of the first 115 named web, a folder, and means for leading all of the strips to said folder.

3. A web printing press comprising a pair of multi-color press units, a single-color press unit, means for guiding a web through one multi-color unit in one direction and through the second multi-color unit, in reverse direction, means for slitting the web into a plurality of strips, means for diverting certain of the strips from the second multi-color unit, means for guiding a second web 120 through the single-color unit, means for slitting the second web into a plurality of strips, means for guiding certain of the latter strips through the second multi-color unit side by side with the portion 125 therein of the first named web, a folder, and means for leading all of the strips to the folder.

4. A web printing press comprising a pair of multi-color press units, a single-color press unit, means for guiding a web through one multi-color unit in one direction and through the second multi-color unit, in reverse direction, means for slitting the web into a plurality of strips, means for diverting certain of the strips from the second multi-color unit, means for guiding a second web 135 through the single-color unit, means for slitting the second web into a plurality of strips, means for guiding certain of the latter strips through the second multi-color unit side-by-side with the portion 140 therein of the first named web, a folder, and means for leading all of the strips to the folder.

5. A web printing press comprising two multi-color press units, two single color perfecting press 150

units, means for passing a web through one of the single color perfecting units and thence through one of the multi-color press units, means for slitting said web into a plurality of strips, means for 5 guiding certain of said strips in reverse direction through the second multi-color unit, means for passing a second web through the second single color perfecting unit, means for slitting the latter web into a plurality of strips, means for guiding certain of the latter strips through the second multi-color unit side by side with the strips of the first web passing therethrough, a folder, and means for assembling all of the strips in superposed relation and leading them as a unit to said folder. 80
